FIG. 6

FIG. 7

A

FIG. 5

UNITED STATES PATENT OFFICE

CLARENCE A. KEEBLER, OF WAUKESHA, WISCONSIN

FOLDING IRONING-BOARD STRUCTURE

Application filed July 17, 1929. Serial No. 378,932.

The invention relates to folding ironing-board structures.

An object of the invention is to effect improvements in that type of ironing-board structure in which the ironing-board, after being swung to a horizontal position, is capable of being adjusted angularly in order to facilitate ironing and to avoid interference with adjacent articles or passages in the room.

Another object of the invention is to provide an ironing-board adapted to be housed in a closet and, when folded, being disposed within the closet adjacent a side wall thereof, in order to permit relatively free access to other articles of household equipment stored within the cabinet.

A further object of the invention is to provide an ironing-board structure which is of durable and inexpensive construction and which can be conveniently assembled and mounted in place.

The invention further consists in the several features hereinafter set forth and more particularly defined by the annexed claims.

In the accompanying drawings, Fig. 1 is a sectional elevation through an ironing-board cabinet embodying the invention, the ironing-board being shown in its extended horizontal position and the folded position of the board being indicated by dotted lines.

Fig. 2 is a sectional plan view through the cabinet showing the board in its horizontal position;

Fig. 3 is a detail sectional view taken along the line 3—3 of Fig. 2 to show the mounting of the inner end of the ironing-board;

Fig. 4 is a detail view showing a trunnion socket for the board;

Fig. 5 is a sectional elevation of a modified form of ironing-board structure, the ironing-board being shown in its horizontal extended position;

Fig. 6 is a view similar to Fig. 5 but showing the board in its folded position;

Fig. 7 is a sectional plan view through the cabinet taken along the line 7—7 of Fig. 5, showing the board in its horizontal extended position, and

Fig. 8 is another sectional view through

the cabinet taken along the line 8—8 of Fig. 5.

In that form of the invention shown in Figs. 1 to 4 inclusive, the numeral 10 designates a cabinet which, in the present instance, is placed in a recess formed in a wall 11 and serves as a closet for the reception of brooms and other household equipment. The cabinet is provided with the door 12, indicated in dotted lines in Fig. 2, and also with a shelf 13 at its upper portion.

A metal plate 14 is secured, as by means of screws 15, to the inner face of one side wall of the cabinet 10. A U-shaped metal strap 16 has its intermediate portion swivelled to the plate 14 by means of a pivot bolt 17 and is rotatable on a horizontal axis. A pivot bolt 18 extends transversely between the legs of the U-shaped strap 16 and has pivotally mounted thereon one end portion of a trunnion plate 19, this end portion of the trunnion plate fitting between the legs of the U-shaped strap 16. The opposite end of the trunnion plate 19 is reduced and rounded to form a cylindrical shank 20 which is adapted to removably enter and fit within an upwardly opening bearing socket 21 which is formed in a block 22 secured, as by screws 23, to the inner face of the other side wall of the cabinet. When the shank 20 of the trunnion plate rests in the socket 21, this shank and the pivot bolt 17 are in alignment on a horizontal axis.

An intermediate portion of the trunnion plate 19 is widened and has the narrowed inner end of an ironing-board 24 abutting against its under-side, the ironing-board being pivotally secured to the trunnion plate by means of a pivot bolt 25 held in place by a nut 26. A metal sector plate 27 is secured, as by means of screws 28, to the recessed under-side of the trunnion plate 19 and has its outer curved edge portions projecting from the edge of the trunnion plate and rounded on an arc concentric with the pivot bolt 25. A bracket 30 is secured, as by means of screws 31, to the upper face of the ironing-board 24 and includes a portion which overlies the marginal portion of the sector plate 27, a thumb screw 32 being threaded in the bracket 33.

and bearing against the sector plate to lock the board in any desired angular position with respect to the trunnion plate, one of such angular positions of the board being shown 5 in dotted lines in Fig. 2. Preferably, the marginal portions of the sector plate 27 are provided with a central recess 33 to receive the thumb screw and thereby determine a central position of the board to facilitate 10 folding of the board, as hereinafter described. If desired, the sector plate may be provided with other recesses similar to the recess 33.

A brace member 34 has one end pivotally 15 secured, as by means of a wide hinge 35, to an intermediate part of the under-side of the board and has its lower end provided with a shouldered pivot pin 36 which removably fits for rotation in an apertured plate 37 secured 20 to the bottom wall of the cabinet, when the board is in the horizontal extended position seen in Fig. 1. The end of the pivot pin 36 and bolt 25 are in alignment on a vertical axis to permit the board to be angularly 25 adjusted.

The ironing-board 24 when in its horizontal operative position is capable of being 30 swung on its pivot bolt 25 in either direction to suit either right-hand or left-hand persons. An angular position of the board is desirable in limited quarters to avoid interference with adjacent objects or passageways in the room.

When the ironing-board is to be folded 35 within the cabinet, the free end of the board is lifted to release the pivot pin 36 from the plate 37 and the board is then tipped upwardly to release the trunnion shank 20 from the bearing socket 21, whereupon the board 40 is swung upwardly and laterally about its universal joint connection to the dotted line position seen in Fig. 1, such universal joint being formed at the swivelled member 16. The ironing-board may be retained in this 45 position by its entrance into a notch 38 formed at one end of the shelf 13. To facilitate the folding and unfolding of the board, the brace member 34 is provided with a projection 39 engageable with a spring clip 40 secured to the inner end of the board to hold the brace member against the board. A handle 41 is also preferably secured to the under-side of the ironing-board to facilitate the manipulation of the board.

50 When the ironing-board is to be shifted from its folded position to its horizontal extended position, it is released from the notch 38 on the shelf 13 and then swung outwardly and laterally about its universal joint mounting to substantially its horizontal position, whereupon the brace member 34 is released from the clip 40 and the pivot pin 36 of the brace member engaged in the plate 37.

65 When the ironing-board is in the folded position shown by dotted lines in Fig. 1, it

lies close to the side wall of the cabinet and thus avoids interference with the removal 70 from the cabinet of brooms and other articles of household equipment, it being unnecessary to disturb the board when such articles are removed from the cabinet or placed therein.

In that form of ironing-board structure shown in Figs. 5 to 8 inclusive, the numeral 110 designates a shallow frame which is 75 adapted to be secured in a wall recess, or to be secured to the inner face of a closet door. As shown in the drawings, the frame 110 forms a full length cabinet but in some instances it may be shortened to the line 80 "A" as seen in Fig. 5. When the frame or cabinet is mounted in a wall recess, it is provided with the usual door, not shown. The frame includes side members 111 which are connected by upper and lower transverse 85 members 112 and 113 and by a back panel 114 re-enforced by transverse strips 115. A pair of blocks 122, conveniently of hard wood, are secured, as by means of screws 123, to the opposite inner faces of the side 90 members 111 of the frame. The blocks 122 are each provided with a bore 121 which forms a bearing socket. The bores 121 are aligned on a horizontal axis to receive the cylindrical shanks 120 of a trunnion plate 95 119, the trunnion plate being thereby journaled to swing on a horizontal axis.

An ironing-board 124 has its narrowed inner end portion engaging the under-side of the trunnion plate 119 and is pivotally mounted thereon by means of a pivot bolt 125 held in place by a nut 126. A sector plate 127 is secured, as by means of screws 128, to the recessed under-side of the trunnion plate 119 and includes a curved marginal 105 portion projecting from the edge of the trunnion plate 119 and arranged on an arc concentric with the pivot bolt 125. A bracket 130 is secured to the upper face of the ironing-board 124, as by means of screws 131, 110 and includes a portion overlying the sector plate 127 and having threaded therein a thumb screw 132, which is engageable with the sector plate to lock the ironing-board 115 in angularly adjusted position with respect to the trunnion plate 119. The marginal portions of the sector plate may be provided with a central recess 133 to receive the thumb screw when the board is centrally located and, if desired, other similar recesses, not 120 shown, may be formed along the sector plate.

A brace member 134 has its upper end pivotally secured to the under-side of the ironing-board 124, as by means of a wide hinge 135, and has its lower end secured to one leaf of a hinge 142, the other leaf of which carries a vertically disposed pivot bolt 136, secured in a transversely-extending slide member 137. The slide member 137 has shouldered ends 143 slidably mounted 130

in vertically extending grooves or channels 144 formed along the opposite inner faces of the side frame members 111.

The slide member 137 is limited in its downward movement by its engagement with the transverse frame member 112 to determine the horizontal extended position of the ironing-board 124. In this position of the ironing-board, the pivot bolts 125 and 136 are 10 in alignment on a vertical axis to permit the board to be swung angularly with respect to the trunnion plate 119, as indicated by dotted lines in Fig. 7, thus accommodating the preferences of right-hand or left-hand 15 persons and avoiding interference with adjacent objects or passages in the room.

When the ironing-board is to be folded, the board is placed in the full line position seen in Fig. 7 and the free end of the board 20 is lifted to bring the board within the frame or cabinet 110, as seen in Fig. 6. When the board is in folded position, a projection 139 on the brace member engages a spring clip 140 carried on the inner end of the board 25 to avoid accidental falling of the board from its upright position.

What I claim as new and desire to secure by Letters Patent is:

1. In an ironing-board structure, the combination of a cabinet, a transversely extending member having its opposite end portion rotatably mounted on the opposite side walls of said cabinet, one of said end portions having a universal joint connection with said cabinet and the other end portion having a separable connection with said cabinet, and ironing-board secured to said transversely extending member and being swingable about said universal joint connection to a 40 horizontal extended position or to a folded position within said cabinet adjacent a side wall of said cabinet.

2. In an ironing-board structure, the combination of a cabinet, and an ironing-board 45 having its inner end pivotally supported on the opposite side walls of said cabinet, said ironing-board having a universal joint connection at one side wall and a separable connection at the other side wall, and said ironing-board being swingable about said universal joint connection to a horizontal extended position or to a folded position within the cabinet adjacent one side wall.

3. In an ironing board structure, the combination of a cabinet, and an ironing-board having its inner end supported on the opposite side walls of said cabinet, said ironing-board having a universal joint connection at one side wall and a separable connection at 60 the other side wall, said separable connection comprising an upwardly opening bearing socket receiving a shank portion of said board and said ironing-board being swingable about said universal joint connection to a horizontal extended position or to a folded 65

position within the cabinet adjacent one side wall.

4. In an ironing-board structure, the combination of a cabinet, a transversely-extending member having its opposite end portions 70 rotatably mounted on the opposite side walls of said cabinet, one of said end portions having a universal joint connection with said cabinet and the other end portion being separable from said cabinet, an ironing-board pivotally mounted on said transversely extending member for angular movement relatively thereto, and a brace member pivotally connected to the under-side of said board and having a separable connection at its lower 75 end with said cabinet for supporting said board in horizontal extended position, and to permit the angular displacement of said board in a horizontal plane, said ironing-board being foldable upwardly about said universal joint connection to lie adjacent the side wall of said cabinet, whereby to permit relatively free access to other objects in said cabinet when the board is folded.

5. In an ironing-board structure, the combination of a cabinet, an ironing-board having its inner end pivotally supported on the opposite side walls of said cabinet, said ironing board having a universal joint connection at one side wall and a separable connection at the other side wall, and said ironing-board being movable to a horizontal extended position or to a folded position within the cabinet adjacent one side wall, whereby to permit relatively free access to other objects in said cabinet when the board is folded, and a recessed member in said cabinet into which an edge portion of the folded board enters for retaining the board in folded position.

6. In an ironing-board structure, the combination of a cabinet having opposite side walls, a member swivelled on one of said side walls to rotate on a horizontal axis, a pivot member secured to said swivelled member to extend at right-angles to the axis of said swivelled member, and an ironing-board having an inner end mounted at one side on said pivot member to form with said swivelled member a universal joint and said ironing-board at the other side of said inner end having a detachable bearing connection with the adjacent side wall of the cabinet, said board being movable to a horizontal extended position or to a folded position within the cabinet adjacent the side wall of the cabinet on which said swivelled member is mounted, whereby to permit relatively free access to other objects in said cabinet when the board is folded.

7. In an ironing-board structure, the combination of a frame including spaced side members having substantially upright channels formed along their opposite inner faces, a transversely extending member pivotally mounted in said frame for swinging move- 125 130

ment on a horizontal axis, an ironing-board having a pivotal connection with said transversely extending member for swinging movement thereon in the plane of the board,
5 a brace member disposed below said board and having its upper end pivotally connected therewith, and a cross member slidably mounted in the channels of said side members and having a pivotal connection with the
10 lower end of said brace member arranged on a vertical axis, said last-named pivotal connection and said first-named pivotal connection being aligned on a vertical axis when the board is in horizontal position, whereby to
15 permit angular adjustment of said board in a horizontal plane.

8. In an ironing board structure, the combination of a supporting frame, a transversely extending member having its opposite
20 end portions rotatably mounted on said frame to swing about a horizontal axis, an ironing board pivotally mounted on said transversely extending member for angular movement, a sector plate secured to a face of said trans-
5 versely extending member, a bracket secured to said board adjacent the periphery of said sector plate and having a lug overlying said plate, a thumb screw threaded in said lug to engage said sector plate for locking said
30 board in adjusted angular position, and means disposed below said board for sustaining said board in a horizontal position.

In testimony whereof, I affix my signature.
CLARENCE A. KEEBLER.
